UNITED STATES PATENT OFFICE.

WILLEM CAREL OLLAND, OF UTRECHT, NETHERLANDS.

APPARATUS FOR PARCELING COINS.

No. 892,878.

Specification of Letters Patent.

Patented July 7, 1908.

Application filed June 28, 1907. Serial No. 381,364.

To all whom it may concern:

Be it known that I, WILLEM CAREL OLLAND, a subject of the Queen of The Netherlands, residing at No. 71 Biltstraat, Utrecht, 5 Kingdom of The Netherlands, have invented certain new and useful Improvements in Apparatus for Parceling Coins, of which the following is a specification.

The present invention relates to apparatus 10 for quickly and automatically counting coins and dividing large quantities of coins into equal lots or parcels, the coins being first piled in a number of approximately equal heaps, while the lowest coin of each 15 pile is transferred to a separate receptacle for each heap or pile. These coins can be delivered into envelops, by which term I mean packets, bags or other receptacles of any kind suitable for the purpose, the machine 20 counting the coins automatically and stopping delivery at a certain predetermined number. For this purpose the coins are dropped through an adjustable hopper on to the apex of a cone, over the surface of which 25 they distribute themselves automatically in an approximately uniform manner, and are caught in open ended tubes arranged in a circle, through which tubes the coins are dropped in succession on to an annular 30 table. The revolving central portion of said table is provided with a number of finger-like projections, one for each of the tubes, which projections always push the lowermost coins away towards a guide tube 35 by which they are conducted into envelops the capacity of which may correspond to the number of coins they are to contain. At the same time as the lowermost coins are pushed away a counting device is set in action. 40 The full packets of coins obtained in this way are then removed either by hand or automatically, and are replaced by empty ones. A special device is provided whereby the rotation of the central portion of the annular 45 table is stopped and a conveyer carrying the coin packets is turned, as soon as the position of all the counting devices is the same, *i. e.* as soon as the predetermined number of coins has passed into each of the 50 envelops. The corresponding position of all the counting devices is controlled by the completion of an electric circuit.

One example or embodiment of the invention is illustrated in the accompanying 55 drawings in which:—Figure 1 is a side eleva-

tion and Fig. 2 a plan; Fig. 3 shows one of the counting devices on a larger scale; and Figs. 4 and 5 show a portion of the automatic checking device, also on a larger scale.

The coins suitably conveyed, as by a belt 60 or a cup elevator, are dropped into a funnel shaped hopper, (Fig. 1) terminating in a tube 2, which is provided with an inverted funnel 3. Under and concentrically with said funnel 3 is arranged a cone 4, turned to a 65 uniform pitch on all sides, over which the falling coins distribute themselves in all directions. Around the outer edge of the cone 4 are arranged a number of hoppers 5, the sector-like orifices of which lie in a circle so 70 that each of these hoppers takes up a practically equal number of the uniformly advancing coins to enable the uniformity of distribution to be adjusted, the hopper 3 is adjustable over the cone 4. The hoppers 5 75 deliver into cylindrical guide tubes 6 which have a rather larger diameter than the coins themselves and are long enough to take a column of say 50 to 200 coins.

An annular flat table 7 is mounted under 80 these guide tubes 6 and at a certain distance from the lower edge of same so that there is just sufficient room for the lowermost coin to be pushed away. This pushing is effected by a rotary disk 8, carrying a number of 85 fixed fingers 9 and mounted within the annular plate 7 so as to rotate on a vertical shaft. These fingers project over the edge of the table about as far as the middle of the guide tubes 6. The height of the fingers is 90 about the same as that of the coins, so that the fingers are able to pass between the table and the lower edge of the guide tubes 6, carrying with them the lowermost coin in 95 each of such guide tubes and pushing it into an adjacent orifice 10 (Fig. 2) in the annular table 7. Hence if the number of fingers on the disk 8 is the same as the number of tubes 6, the number of coins pushed away in a 100 single revolution of the disk 8 will be equal to the square of the number of tubes, so that in the event of there being ten tubes, for instance, a hundred coins will be pushed away during each revolution.

Mounted radially outward from each tube 105 is a counting device (Fig. 3) having ratchet teeth corresponding in number to the number of coins which are to make up a parcel, *e. g.* 25, 40 or 50 teeth; and these are numbered accordingly. The counter is moved to 110

the extent of a single tooth only when a coin is actually pushed from the tube into the orifice 10.

- The arrangement of the counter is as follows: A two-arm lever 12—13 is rotatably mounted on the shaft 11 (Fig. 3). The arm 13 is of about the same thickness as a coin. The end of the arm 12 carries a bell-crank lever 14, which is jointed thereto and forms a pawl for the counting wheel 16. This pawl is kept pressed into the teeth of the wheel 16 by a coiled spring 15, back motion thereof being limited by the stop block 17 (Fig. 3). Each coin as it leaves the tubes 6 is engaged by one of the fingers 9 and pushed against a projection 37 (Fig. 3) on the annular table 7, as also against the end of the lever arm 13. For the sake of clearness this projection is not shown in Fig. 2. On the advance of the finger 9, the lever arm 13 is turned by the coin, whereby the pawl 14 is caused to slide over the back of the ratchet teeth and to click into the next tooth as soon as the coin has released the arm 13. At this instant the coin falls down into the hole 10, the coiled spring 15 pulls the ratchet wheel forward a distance of one tooth and the arm 13 back into its original position. This operation is repeated for each coin. The stop 17 prevents the ratchet wheel from being moved through a greater distance than the length of one tooth. Another pawl 18 actuated by a coiled spring is intended to prevent the pawl 14 pushing back the ratchet wheel under the influence of the spring 15 by which it is kept pressed against the periphery of the ratchet wheel. The above described device insures the counting wheel being held quite firmly in all directions.
- The table 7 carries, arranged in a circle, as many contact springs 20 as there are counting wheels, the free end of each spring extending beyond or overlapping the point at which the next spring is attached to the table. The co-operating ends of two of these springs are provided with a pair of contacts 55 and 56 which are connected in a circuit including the magnet 23, an electric bell 57 and a battery or other source of current 58, the battery being also connected to the electro-magnet in a manner to be hereinafter described. A pin 19 fixed on the lower face of the ratchet wheel, presses against the contact spring 20 when the wheel is in a certain position, and thus brings the free end of the spring 20 into contact with the point of attachment of the next spring, thereby completing the circuit of the electro-magnet 23 (Fig. 1). This position corresponds with either the zero position of the wheel or else that of the highest number.

It will be evident that the circuit cannot be completed until an equal number of coins, corresponding to the highest number of the teeth on the wheels, has been pushed from

under all the tubes 6. The completion of the circuit first rings the bell 57 and then, by means of the electromagnet 23, releases a stop motion, whereupon the filled packets of coins can be taken away. Such stop motion will hereinafter be more fully described.

Below the holes 10 are provided hoppers and guide tubes 38 through which the coins are directed into envelops 39, suspended from a belt conveyer 24, and made of cardboard or similar suitable material. The belt conveyer 24 is, as shown in Fig. 2, passed round a horizontal pulley mounted outside the machine and round the pulley 25 placed on the same horizontal level and equal in diameter to the disk 8. The envelops are suspended in corresponding holes in the belt, and pass under the openings of the guide tubes 38 as the belt is moved. The movement of the belt 24 and the rotation of the disk 8 are effected by the worm 27, which drives the shaft 28 by a worm wheel 46, the movement of the said shaft being transmitted by bevel gears 47 and 48, the shaft 49, and friction gear 50, to the belt conveyer. The same shaft 28 operates both the belt conveyer 24 and the disk 8, through the bevel wheels 29, 30, the shaft 31, pinions 32, 33, shaft 34 and friction wheels 35 and 36, in such a manner that the friction wheels 50 and 35 do not drive the belt conveyer at the times when the disk 8 is turning, said conveyer consequently remaining stationary at such times, and conversely the gear wheel 36 cannot operate the revolving disk 8 during the time when the belt conveyer is in motion, and when said disk is accordingly intended to remain stationary.

The device for temporarily suspending rotation of the disk 8 while leaving the belt conveyer free, and vice versa, is arranged as follows: Under the disk 8 is a cam 51 which makes a quarter turn for each revolution of the ratchet wheel 21, by engaging with one of the four teeth 52 arranged on the ratchet wheel. A notch or depression 53 (Fig. 4) is provided in the contour of the wheel 21; and underneath this wheel is a flexibly mounted lever 22 having a feather or projection suitably located thereon to engage the notch. This lever 22 in turn is connected with a vertically mounted bar 26 the lower end of which is adapted to freely enter a hole 43 in the pulley 25, while the upper end 42 of same can engage with a lug 41 on the disk 8. The bar 26 is also connected with a two-arm lever 44, the other end of which forms or carries the armature of the electromagnet 23 which as already stated, is connected in the circuit of the contact springs 20. The lever 44 is held in equilibrium by a spring 40. The result is that the ratchet wheel 21 making one revolution to every four revolutions of the disk 8, the notch 53 is brought into position opposite the projection or feather, where-

upon the lever 22 engages with said notch which permits the ascent of the bar 26, the upper end 42 of which locks the lug 41 which has meanwhile been carried round by the disk 8 into position in front of the bars. By this means any movement of the disk 8 is prevented. At the same time the lower end of the bar is partly drawn out of the hole 43 in the pulley 25. The complete release of the belt conveyer 24 is effected by the electromagnet 23, since after the disk 8 has made four revolutions all the counting devices have reached the maximum figure, all the contact springs 20 are connected up, and the armature of the lever 44 is attracted, thus drawing the bar 26 entirely out of the hole 43, and enabling the pulley 25 to turn with the belt conveyer.

The only movement required of the belt conveyer at each step is to enable a set of envelops 39 to be inserted in place of the full ones. As soon as this is done, the motion of the belt must be checked, the bar 26 being intruded into the hole 43. This is effected by means of the following device: The revolving pulley 25 is provided at its under side with an annular contact ring 54 having an insulating plate 59 set therein. A contact stud 60 which has an insulated mounting in a bracket 61 secured to the bearing for the shaft of the revolving pulley 25 is arranged to engage against the said contact ring. The contact stud 60 is electrically connected to the battery 58 while the contact ring 54 is connected to the bearing for the pulley 25, the latter being connected electrically to the magnet 23 as shown in Fig 2. The contact stud 60 passing over the insulating plate 59 breaks the circuit of the electromagnet 23 shortly before the hole 43 again comes under the bar 26, consequently the armature is released, and the spring 40 pulls the bar down, thus passing it against the upper face of the pulley 25, while the lug 41 of the disk 8 still remains in contact with the top edge 42 of the bar 26. As soon, however, as the hole 43 has arrived, underneath the bar, the latter drops into same, thereby locking the belt conveyer and releasing the disk 8, which thereupon again begins to turn.

As already mentioned the signal bell 57 is connected up in the circuit of the electromagnet. If the bell fails to ring after four revolutions, notwithstanding that the stop motion 21, 22 has stopped the disk 8, this indicates that some of the counting devices have not reached their maximum figures, and the cause of the error may be traced.

The operation of the apparatus is briefly as follows: All the counters having been set to zero, the feather on the lever arm 22 is adjacent to the notch 53 in the ratchet wheel 21, so that, the cam 51 coming into position against one of the teeth 52, the bar 26 releases the lug and drops into the hole 43 in the

pulley 25; and when, furthermore, empty envelops have been placed in the holes in the belt conveyer the driving mechanism 27 is started and a quantity of coins is emptied into the hopper 1. The coins slide down over the surface of the cone 4, and through the guide tubes 6 to the annular table 7 where they are engaged by the fingers 9 of the revolving disk 8 and pushed into the hole 10, the counting wheel being turned one tooth every time. The coins then fall through the guide tubes 38 into the envelops 39; and assuming each envelop to be calculated to hold say 40 coins and the machine to be provided with ten counting devices, 80 guide tubes 6 and fingers 9, and all the ratchet wheels to have 40 teeth, then the packets will be filled with coins in four turns of the disk 8. At the same moment the motion of the disk 8 is checked and the bar is drawn up out of the hole 43 in the pulley 25, whereupon the belt conveyer with the ten envelops full of coins advances until ten empty envelops have taken the place of the filled ones. At this moment the motion of the belt conveyer is checked. The filled envelops are removed, replaced by empty ones, and the whole series of operations repeated.

What I claim as my invention and desire to secure by Letters Patent is:—

1. A coin handling machine comprising a hopper, a set of chutes, a transferring member common to all the chutes for conveying the coins from the hopper to the chutes, a device individual to each chute having means for advancing it a step for each coin actually conveyed to the chute, and an indicator controlled by said devices of all the chutes for indicating whether all the chutes have received a full number of coins.

2. In a coin packaging machine, the combination with a coin chute, and an annular row of stacking devices, of a distributor centered axially of the chute and concentrically of the stacking devices for directing the coins into the latter, a plurality of envelop supporting devices, and a revoluble transferring member common to all the stacking devices and having a plurality of fingers rigidly fixed thereon for conveying the coins from the stacking devices to the corresponding envelops.

3. In a coin packaging machine, the combination with an annular row of stacking devices, and means for distributing the coins thereto, of a corresponding row of envelop supporting devices arranged below the stacking devices, an operating element for revolving the envelop supporting devices, a rotatable disk having means thereon for transferring the coins from the stacking devices to the corresponding envelops, and a stop-motion arranged to coöperate alternately with the said disk and element for interrupting the movement of the disk and permitting

movement of the operating element for the envelop supporting devices.

4. A coin handling machine comprising a hopper, an annular row of coin chutes arranged to receive coins from the hopper, a corresponding row of coin-stacking tubes, means common to all the chutes for transferring the coins therefrom to the respective stacking tubes, a counting device individual to each stacking tube, and a signal common to all the counting devices and set in operation only when all the counting devices register a full number of coins for each tube.

5. A coin handling machine of the class described comprising a coin receiving hopper, an annular row of coin-stacking tubes, a member for transferring the coins from the hopper to the respective stacking tubes, a conveyer having means for supporting a plurality of envelops in an annular row beneath and in alinement with the respective stacking tubes, a counting device for each tube, and a locking device for the conveyer releasable by the counting devices when they all register a full number of coins for each envelop.

6. The combination of a coin hopper, a plurality of means for piling coins into separate heaps, a cone between said hopper and the piling means adapted to distribute or apportion the coins among the piling means, means for supporting a plurality of envelops, and means for loading predetermined numbers of coins from the several piles into the envelops.

7. The combination of a coin hopper, a plurality of means for piling coins into separate lots, a cone between said hopper and the piling means, said hopper being adjustable relatively to the cone, an annular support adapted to receive the piled coins, a rotatable device adapted to push away the bottom coin in each pile, a support adapted to carry a plurality of envelops, guides in the paths of the several pushed away coins adapted to load same onto the envelop support in separate lots, counting means for the several lots, and means for stopping a loading means when a predetermined number of coins have been loaded thereby.

8. The combination of a plurality of means for piling coins into separate lots, means for feeding coins to said several piling means, a movable conveyer adapted to support a plurality of envelops below said piling means and having accommodation for a fresh supply of envelops remote from the piling means, means for transferring coins from the piles to each of the envelops below the piling means, and means for determining the number of coins to be delivered by each of said transferring devices.

9. The combination of a traveling conveyer, means for feeding coins to same, means for driving said conveyer, electrically operated means including contacts for

controlling the motion of said conveyer, counting mechanism for determining the number of coins delivered to said conveyer and means operated by said counting mechanism for closing said contacts so as to permit motion of the conveyer.

10. The combination of a belt conveyer, means for feeding coins to same, means for moving said conveyer, means for locking said conveyer against motion, means including an electromagnet for releasing same, a contact in the circuit of said electromagnet, counting mechanism including a rotary part, and means carried by said rotary part for closing said contact.

11. The combination of a conveyer, means including a rotary part for feeding coins to said conveyer in separate lots, means for driving said conveyer, locking means between said rotary part and said driving means, means for actuating same one way to lock said rotary feeding part and means for actuating said locking means the other way to lock the conveyer drive.

12. The combination of means for parceling out coins into lots, a conveyer, means for conducting the coins of the several lots separately to said conveyer, means for driving said conveyer, a lever, an electromagnet for actuating same in one direction, an oppositely acting spring, means for closing the circuit of said electromagnet at predetermined times, a locking bar carried by said lever and adapted on one motion thereof to lock the parceling mechanism and on the opposite motion to lock the conveyer driving mechanism.

13. The combination of means for piling coins into a plurality of separate heaps, means for withdrawing coins from said heaps simultaneously, coördinate mechanisms for counting each lot of coins so withdrawn, a bar for locking said withdrawing means, means for normally keeping said bar out of engagement with the withdrawing means, means for positively actuating said bar to lock same and means adapted to be jointly controlled by all the counting mechanisms for setting said actuating means in operation.

14. The combination of means for feeding coins into a plurality of piles, a rotary pusher for withdrawing coins from all of said piles simultaneously, a bar for locking said pusher, means including a ratchet wheel such as 52, a contour cam such as 21 and a yieldable lever such as 22 for normally holding said bar out of locking position relatively to the pusher but releasing said bar after a predetermined number of revolutions of the pusher, and means adapted on the release of the bar to positively interlock same with the pusher.

15. The combination of means for feeding coins into a plurality of piles, a rotary

pusher for withdrawing coins from all the piles simultaneously, coordinate mechanisms for counting each lot of coins so withdrawn, a conveyer adapted to receive the several lots, means for driving said pusher, means for driving said conveyer, electrically controlled means for alternatively locking the pusher and the conveyer drive, contacts in the circuit of said controlling means corresponding with the counting mechanisms, and means operated by said counting mech-

anisms for closing the respective contacts when a predetermined number has been reached by each.

In testimony whereof I have hereunto 15 set my hand in presence of two subscribing witnesses.

WILLEM CAREL OLLAND.
